LAND MINE EXPLoder DEVICE

Allison R. Williams, Yazoo City, Miss.

Application January 21, 1944, Serial No. 519,142

6 Claims. (Cl. 262—13)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to a method of and apparatus for applying pressure either to the earth's surface or to any flat or approximately flat surface at a plurality of points progressively, according to a prearranged pattern. More particularly, the invention provides for the pressure application by impact and sustained effort by relatively simple and light apparatus capable of exerting extremely heavy pressure.

The invention contemplates numerous applications, for example, earth tamping, breaking up hard sheet material such as sheet concrete and thick ice, surface exploration, military mine field clearing and the like, especially where the application makes impact and sustained pressure desirable.

Apparatus according to the present invention is capable of readily exerting pressures even as much as several thousand pounds per square inch using relatively simple and light apparatus. Since the impact force increases as the square of the velocity, and the area of impact may be reduced by employing a pointed case hardened compacter element, the mechanism may, by proper coordination of these two factors, be caused to exert tremendously high compacting stresses.

The apparatus herein contemplated is simple and compact, is readily transported, and lends itself readily to breaking the concrete into small, and easily handled pieces. The machine may, moreover, be designed to produce sections of any desired size.

The breaking of thick sheet ice on bodies of navigable water to provide for navigation under severe winter conditions also presents a difficult problem. Special ice-breaking vessels are used for this purpose as vessels of ordinary construction are not suitable. Apparatus of the present invention can be readily adapted to use in ice breaking without special propelling equipment and can, therefore, be attached to and be driven by any vessel, thus making each vessel capable of functioning as its own ice breaker.

It is well recognized that the planting of extensive mine fields serves an important tactical function in denying the use of strategic areas such as airports and highway facilities to a pursuing force. Many expedients have been tried in attempts to locate and destroy, remove, or otherwise render ineffective such mine fields. When location and removal are attempted manually,

2

enemy action and the presence of occasional booby traps, and anti-personnel mines expose the removing and locating personnel to great danger. Most of the machines which have been tried in efforts to explode the mines without exposing personnel have been of such a character that the exploding device was itself destroyed or seriously damaged by any exploded mines. Certain other of the mechanical arrangements employed have raised such clouds of dust as to cause serious difficulty with engine air cleaners and to necessitate "buttoning up" the tank or other propelling vehicle and driving in accordance with directions given by radio. Other devices which have been employed have caused such disturbance of the ground surface as to require consolidation of the ground before it could be again used as an airport, for example, and some have had the bad habit of throwing exploding mines onto or under the vehicle propelling the mine exploding device.

The extension use which is made of land mines in modern warfare makes it essential that some effective means be developed which is capable of destroying the mines in place without being itself destroyed, and which operates with a minimum of disturbance to the surface of the ground.

Having the factors above mentioned in mind, it is one of the purposes of this invention to provide a compacting device capable of adaptation to any of the above uses and capable, when it is employed as a mine exploding device, of functioning effectively, and of absorbing the shocks of repeated mine explosions without significant damage to the equipment.

It is a further object of this invention to provide a mine exploding device which can be operated with a minimum input of energy, which will leave the surface of the ground in which there are no mines in condition for immediate reuse, and which will cause a minimum of disturbance in the ground adjacent an exploded mine.

It will be obvious to those familiar with the nature of explosive reactions that a minimum disturbance of the surrounding ground surface will take place when a mine is detonated without much confinement. An ideal condition would be one in which the mine could be detonated in place confined only by the shallow covering of earth above it. In such a case, the force of the explosion would be dissipated harmlessly in a substantially vertical direction.

Such an ideal condition would be closely approximated by causing the end of a stafflike hammer member to impinge upon the mine with suffi-

cient force to cause explosion thereof. In the case of such a body having a diameter small in relation to its length and weight, the requisite force could be applied without substantial confinement of the explosion, and with a relatively small amount of kinetic energy being imparted to it.

In a practical embodiment of such a device, there may be provided a plurality of hammers provided with elongated heads for impingement upon the ground, and operatively connected to a propelling vehicle in spaced relation to each other. Such hammers may be operated to cause the heads to reciprocate in a substantially vertical direction, and if the assembly is moved forwardly at a rate properly coordinated with the rate of reciprocation, the heads may be caused to impinge upon the ground at spaced intervals in accordance with a predetermined pattern. Proper choice of the physical constants of such an arrangement can be made to produce a pattern of points of impact so closely spaced across the path of movement, and along the same, as to compact a substantial portion of the area traversed, and where the device is employed for mine clearing to make it impossible for any pressure sensitive mine in the area covered to fail to be activated. Such a construction will present a minimum of projected area to the blast and suitable means may be provided to allow the hammer to yield with the blast or to absorb the energy received therefrom either as internal stress or with other energy-absorbing means, such as hydro-spring or hydro-pneumatic recoil mechanism.

Experimental determinations have supported a conclusion that if, in using the device for mine field clearing, the projected area of the hammers be kept at a minimum commensurate with adequate mechanical strength, and the weight applied thereto be increased, a point may be arrived at where the mass of the hammer will itself be sufficient to absorb the energy of the explosion without imparting appreciable velocity to it. If bodies of lighter weight be used, it has been found that suitable spring or shock absorbing means may be profitably utilized to absorb a part of the energy from the blast without damage.

Experimental work has also proved that a shaft-like member fitted with a foot of relatively hard material and having a length relatively great in relation to its diameter, may have its hardened surface exposed to the explosion of a land mine without significant damage other than a moderate erosive action on the surface exposed directly to the blast.

When the invention is embodied in a mine clearing device, it may be moved over a mined area by an armored vehicle, such as a tank or the like, so as to explode by direct impact any mines which may have been sown in the area to be cleared. It is to be understood that the apparatus can be either pushed or pulled and that manual, as well as mechanical, propulsion is possible. For military uses, it is desirable that the operating personnel be shielded from enemy fire, and from the blast of any mines detonated by the device, hence, reference is made to an armored propelling vehicle, but it is to be understood that the illustration made is intended to be exemplary and not limiting in character.

The exact nature of the invention, as well as other objects and advantages thereof, will be apparent from this description of certain em-

bodiments shown in the accompanying drawing in which:

Figure 1 is a side elevation of a single elementary impact member together with actuating means capable of embodiment in devices of the invention;

Figure 2 is a top plan view of the forward portion of a tank having a complete embodiment of my invention mounted thereon and showing one type of impact pattern which may be produced;

Figure 3 is an enlarged top plan partially in section, of a portion of the unit illustrated in Figure 2;

Figure 4 is a side elevational view corresponding to Figure 2;

Figure 5 is a side elevational view of a compacting element, the view illustrating diagrammatically the path followed by one of the compacting elements referred to a plane moving forwardward at the same velocity as the propelling vehicle and compacter assembly;

Figure 6 is a diagrammatic view illustrating the path followed by the tip of the compacter element with relation to the ground, as the tank and compacter assembly moves forward;

Figure 7 is a vertical sectional view, partially in elevation, and with parts broken away, of a preferred form of compacter unit in which a hydro-spring energy absorbing means is employed;

Figure 8 is a sectional view illustrating a combined hydraulic and pneumatic energy absorbing means capable of use with compacter units embodying the invention;

Figure 9 is a top plan of the energy absorbing device of Figure 8;

Figure 10 is a vertical sectional view of another form of energy absorbing device operating hydro-pneumatically and capable of use with compacters of the present invention;

Figure 11 is a vertical sectional view of a further modified form of compacter element with a pneumatic energy absorbing means, the compacter support and actuating means being also shown; and

Figure 12 is a top plan view of a means for controlling the elevation of a compacter assembly.

The invention will now be described as embodied in a mine field clearing device, not only because the broad concept first arose in connection with tactical problems encountered by an army in the field, but also because it affords an excellent illustration of the practical aspects of the invention. In its simplest form, the device consists merely of a plurality of impact elements or hammers arranged to be brought successively into forcible contact with the surface of the ground according to a predetermined pattern. The spacing of the points of impact depends not only upon the number and location of the compacting element, but also upon the periodicity of their actuation as determined by the propelling mechanism for the compacter assembly and the arrangement of the actuating mechanism of the individual units.

From the above it follows that by suitably proportioning the mass of the compacter elements and the rate at which they are driven so that the energy expended by the impact of a compacter element substantially balances the energy expended by an exploded mine, the upward and downward forces oppose each other and substantially balance. This is an ideal condition in that it reduces the weight of the compacter elements and the supporting mechanism, cuts down

the power required to drive the device, and makes it possible to materially reduce damage to the compacter by the exploding of mines beneath it. Under such balanced conditions of operation, the strength of the compacter assembly need be only great enough to withstand the mechanical pounding to which it is subjected as the device traverses rough and stony or uneven terrain. This mechanical pounding may be reduced materially by providing shock absorbing means in the compacter elements or in the mounting means or in both of them.

In this description, several embodiments of the invention will be referred to in order to indicate the broad scope of the concept, but numerous other and equivalent applications will occur to those skilled in the art, and this specification is, therefore, to be construed as exemplary only.

Figure 1 of the drawing is intended to illustrate the invention in simple elementary, and more or less diagrammatic, form. Here reference character 13 designates a metal compacter element in the form of a hammer streamlined to present a minimum area to an upwardly acting explosive blast, and preferably having its lower end or foot of such hardness and chemical composition as to resist mechanical damage from impact, and erosion from gases liberated by exploded mines.

When the elements are employed for impact only, mechanical damage only need be provided for. The element 13 is supported by an arm 14 adapted to rock about a fulcrum 15 moving in slot 16 in the arm, the arm being actuated by an eccentric 17 carried by a rotating shaft 18. It will be apparent that as the shaft and eccentric rotate, the element 13 will execute an up-and-down motion in an approximately vertical line and that by suitable design of the slot, the arm and the eccentric, the element may be arranged to move in any desired path. This arrangement is, therefore, merely a mechanically-driven hammer which may be duplicated to form an assembly similar to that shown in Figure 2.

Referring now to Figure 2, reference character 19 designates a propelling vehicle, here shown as a tank, and having mounted thereon a compacter or exploder device made up of two groups of units each receiving power from the tank. As shown in Figure 3, each group has a drive shaft 21 mounted in suitable bearings 22 carried by the body structure of the vehicle. A clutch 23 applies power to the shafts 21 from the forward drive shaft 24 of the tank through suitable gearing indicated generally at 25, it being understood that both shafts 21 are driven similarly.

Eccentrics 26 carried by the shaft 21 actuate short arms 27 and long arms 28, each arm carrying at its outer end a compacter element C secured in place as indicated in Figure 4. The eccentrics and the arms which they drive are suitably spaced along the shaft 21 so as to properly relate the points of impact of the various elements C. Each arm carries a bushing 29 slidably mounted on it, each bushing carrying in turn two rocker pivots 31 received in journals 32 in housing 33 surrounding the eccentric mechanism and journaled on the shafts 21. As shown, two housings 33 are provided, one for each group assembly on each shaft 21, but the arrangement of the housing may be varied to suit convenience. Connected to each housing 33 is an elevating device in the form of a cable 34 attached to it centrally as at 35 and passing over guide pulley 36. By tightening or releasing the cable, either housing, and the compacter group assembly to which it is attached,

may be elevated to inoperative position or adjusted to a suitable height to meet conditions such as rough terrain, muddy terrain, barbed wire entanglements and the like. Either unit may be 5 adjusted independently of the other, as, for example, when one unit is on lower ground than the other. Also, the number of groups may be increased to provide more flexibility of operation over uneven terrain, the illustration of two groups 10 being merely by way of example.

It will be obvious that as the drive shafts 21 are rotated by the forward drive of the tank or any other suitable vehicle means, each of the arms 27 and 28 will swing about an axis extending 15 through the rocker pivots 31. By suitable adjustment of the inclination of housings 33, it will be apparent that during rotation of the shafts 21, each compacter member may be caused to strike the ground a blow of considerable force, and by 20 proper selection of the speed rates between the forward drive and the shafts, these impacts may be caused to occur at definitely spaced intervals so close to one another as to make it impossible for any pressure sensitive mine in the path to be 25 cleared to be left untouched. The lateral spacing of the compacter elements will be such as to complete a checkerboard pattern of impacts as illustrated, or any geometrical pattern, regular or irregular, to effectively cover the area to be traversed.

In arranging the compacter elements C to effectively cover the area to be cleared, it is desirable to, at the same time, space the elements far enough apart to confine the effects of the explosion of a mine detonated by one element to that particular element. The use of alternate short and long actuating arms 27 and 28 achieves this result without sacrificing distance. The inter-positioning of the elements on the shorter arms 30 27 increases the spacing of the elements on the longer arms 28, and, hence, protects the outer row of elements without increasing the spacing of the points of impact in the overall pattern.

As shown in dotted lines in Figure 4, the eccentrics of each set of three are spaced 120° apart about the periphery of the shaft 21. In this way, rotation of the shaft will produce a series of impacts in one, two, three order, assuming that 45 two mine explosions will not occur simultaneously within any given group of three compacter units. The next group of three would be similarly spaced within the group, but preferably the group as a whole would be somewhat displaced from the previous group to insure that similar elements of each group did not impact at the same time with the possibility of simultaneous explosions in similar positions in each group. Obviously, simultaneous explosions would greatly multiply the 50 chances of damaging the apparatus. In the particular example shown, each group of elements is offset twenty degrees with relation to the group preceding it, and each element within a group is offset 120° with relation to the other two elements in the group. In this way, an impact order for a 55 group of nine units may be set up as follows: 1, 4, 7, 2, 5, 8, 3, 6, 9. Figures 5 and 6 show diagrammatically the path followed by a given compacter unit as it moves through its cycle of operation. As will be seen from Figure 6, the dotted line path taken by the foot of an element with 60 relation to the ground is not unlike the path followed by the front hoof of a trotting horse in that it strikes the ground and moves up and forward without sliding movement in relation to the

ground. This is important in obtaining sustained pressure at the point of impact.

As has been previously mentioned, cables 34 have been provided as a means of adjusting the inclination of the housing 33 and since the arms are pivoted therein, it will be apparent that the position of the compacter feet with relation to the ground may also be regulated thereby. An electrically operated winch, such as that shown in Figure 12, provides one convenient means of controlling the length of the cable. In actual practice, it will be found that on normally hard terrain the major portion of the unbalanced weight of the compacter assemblies will be borne by the elements in contact with the ground at any given time. Hence the cable may usually be left slack and the compacter feet will walk forward enabling the device to automatically respond to variations in the contour of the earth in its path. When the device is to be moved from place to place without contacting the ground, the cables 34 are wound to elevate the compacter elements above the ground.

As shown in Figures 2 and 4, the cables 34 are attached to the housings 33 and then pass over the guide pulleys 36. The cables may be wound and unwound by any suitable mechanism, either mechanical or electrical. As an example of one form of mechanism which may be provided, there is shown in Figure 12 an electric winch. In Figure 12, the cable 34 is wound on a drum 37 fixed to shaft 38 mounted in bearings 39. A gear 41 is also fixed to shaft 38 and meshes with worm 42 on shaft 43. Shaft 43 journaled at 44 is driven by an electric motor 45. The direction of rotation of the drum 37 is determined by the direction of rotation of motor 45. Any suitable reversing and control mechanism may be provided for the motor, but since such controls are well known, they are omitted from the illustration. Obviously, the control used should provide simplicity and ease of operation with reliability.

Although the device has been shown as split up into two groups, each of which may be controlled individually with regard to height above the ground, it is obvious that this breakdown may be carried even farther with consequent improvement in flexibility and ability to follow rough contours. The two groups together are shown as having substantially the same width as that of the actuating vehicle, but further increases in the number of units not only assists in reducing the probability of damage to the units from exploding mines, but may afford greater compacting range and flexibility. When a greater number of groups is used, they may, and preferably do, extend laterally beyond the propelling vehicle so as to insure adequate width of the compacted area when traveling around curves or making sharp turns. Any permissible increase in width of the compacted area reduces the number of passes required and affords more economical use of the propelling vehicle.

As indicated above, it is possible to so design the apparatus that the explosive impact of an exploding mine places substantially no stress upon the compacter element, as the kinetic energy of the blast is balanced by the compacter element as it is driven downwardly. Therefore, with this balanced operation, the use of energy absorbing devices in conjunction with the compacter elements is not theoretically necessary to protect the mechanism against the destructive impact of a mine blast. Where, however, the forces are not strictly bal-

anced, such devices are useful, and they are always useful in relieving the mechanism of stresses imparted to it by the "pounding" shocks which the mechanism receives as the apparatus operates over a hard surface.

In describing the effect produced upon a compacter element, especially when subjected to the blast of an exploding mine, each of the compacter elements C may be compared with a gun in reverse. By this it is meant that the compacter element which, by impact, causes the explosion of the mine will be propelled in a generally vertical direction away from the explosion. The body of the compacter may be made in the general form of a cylinder in which the foot of the element can move against the resistance of suitable energy absorbing means generally similar to a cannon recoil mechanism to receive and dissipate the shock, while means in general similar to a recuperator mechanism return the compacter foot to its normal operating position. Preferably, the compacter elements and the forwardly extending arms 27 and 28 will be of streamlined form to reduce the amount of force which will be taken up from the blast, and a staggered arrangement of the compacter units will be employed to permit the escape of the gases of the explosion with a minimum of obstruction.

The energy absorbing means employed may assume various forms and may be mechanical, pneumatic or hydraulic, or combinations of these, but it is at present preferred to use a combination of hydraulic and spring means in which the hydraulic means absorbs the recoil and the spring acts as a recuperator. Considered from the standpoint of absorbing mechanical shock as the device operates over the ground both the spring and the hydraulic mechanism act concurrently. The smaller shocks are substantially absorbed by the spring, whereas shocks sufficient to stress and deform the spring cause movement of the hydraulic piston against the opposition of the hydraulic fluid. This action will be set forth in the description of specific embodiments which follows.

A preferred form of compacter incorporating a combination spring and hydraulic energy absorbing means is shown in Figure 7. In this embodiment emphasis is placed upon the design and location of vulnerable parts so as to protect them against damage caused by the blast of exploding mines.

In Figure 7, the foot 46 of the compacter element composed of mechanically resistant and erosion resistant steel, such as hardened armor plate, increases in diameter upwardly until it terminates in a tapered body 47 and a guard sleeve 48. The foot and the body form a smooth taper which offers a minimum opposition to an explosive blast, and the cylindrical guard sleeve 48 encloses and shields the spring and hydraulic mechanism both from mechanical damage and from the erosive effects of burned gases.

Body 47 is countersunk to receive the threaded end 49 of a piston rod 51, and again at 52 to form a seat for the lower end of a spring 53 surrounding the piston rod 51. The spring 53 reacts between the countersink and a guide 54 movable within the sleeve 48. The guide 54 is composed of upper and lower sections threaded together at 55, and the upper section not only carries an hydraulic cylinder 56 threaded to it at 57, but is countersunk to receive a piston 58 formed integrally with piston rod 51. The chamber for fluid is formed between the piston rod 51 above piston

58 and the inner wall of cylinder 56. This wall is contoured, parabolically as shown, to provide predetermined resistance to upward movement of the piston rod as the hydraulic fluid is forced through the orifice formed by piston 58 and the inner wall of cylinder 56 during upward movement of the piston. The cylinder 56 embraces the reduced upper end of piston rod 51 and the joint is sealed by a packing 59, held in a ring 61 threaded into the recessed upper end of cylinder 56. The supporting and actuating arm may be attached to the element by a bracket 62 welded or otherwise secured to the cylinder 56. The guard sleeve 48 may be slotted at 63 to permit free movement of the foot and attached parts without striking the bracket.

It will be apparent that in the structure shown the spring 53, aided by gravity, biases the piston rod 51 and attached parts including foot 46 downwardly to the extreme position shown, while upward movement of the piston rod and foot is opposed not only by the spring, but also by the hydraulic fluid. The parts are preferably so arranged in practice that the overall resistance opposed to the upward movement of the foot 46 by the spring, the hydraulic mechanism and the packings is substantially constant throughout the stroke. When the device is periodically striking a hard surface, as in moving over a mine field, this energy absorbing means cushions the impacts and smooths out the reactions which are transmitted to the compacter supporting means.

The means, is therefore, effective to reduce wear and tear on the apparatus occasioned either by mine blasts or by mechanical impact, or by combinations of the two. Furthermore, the expensive and vulnerable parts in the mechanism are protected by guard sleeve 48 against metal fragments and explosion gases. This not only prolongs the usefulness of the mechanism, but avoids welding of the parts together by the heat of explosions, as may occur when the exposed parts are in several pieces. Consequently, the foot 46 and parts integrally attached to it can always be removed and replaced when the foot has been abraded or eroded to a point where it is no longer useful. In this way, the most vulnerable part of the compacter, namely the foot, can be replaced at intervals to not only reduce materially the weight of spare parts to be carried, but also to reduce the frequency and extent of servicing required.

Figures 8 and 9 show a preferred form of hydro-pneumatic absorbing means in which a flexible metal bellows containing air or other gas is disposed in a chamber laterally of the hydraulic piston chamber, and it provides the advantage of a double end support for the piston, of small displacement of liquid, and also of utilizing a simple and conventional type of metal bellows.

In Figure 8 all parts of the compacter except the absorbing mechanism are omitted for simplification. It will be understood that any type of foot previously described may be utilized. The piston rod 64 in this figure has its lower end guided in a fitting 65 secured to barrel 66. This fitting is threaded into or otherwise secured to the barrel 66 and serves not only to guide the piston rod 64, but also to form the bottom of the hydraulic cylinder 67 and of the bellows chamber 68. The two chambers are filled with hydraulic fluid but are separated by a wall 69 terminating below the cover plate 71 for the two chambers so as to provide a liquid flow path 72.

The cover plate 71 contains a stuffing box 73 which seals the upper reduced end of the piston rod 64 with respect to the fluid chamber.

The piston rod 64 carries a piston 74 and is of much reduced diameter above the piston. The bellows chamber 68 contains a Sylphon bellows 75 supported from the cover plate 71 and having a charging fitting 76. The Sylphon is exposed to pressure by liquid fed laterally from the piston chamber into the Sylphon chamber and, therefore, serves not only to oppose upward movement of piston 74, but tends to restore the piston 74 to the position shown in the drawing. The charge of air or other gas in the bellows may be varied to secure widely varying opposing pressures. The difference in diameter of the piston rod above and below the piston 74 makes it possible to utilize a relatively small bellows. The amount of liquid transferred to the bellows chamber is determined by the difference in these rod diameters, hence the liquid volume to absorb a given pressure in the bellows is much less than would be the case if the rod were of the same diameter below the piston that it is above it.

Figure 10 illustrates still another form of compacter element embodying hydro-pneumatic energy absorbing means. In this form the rod 77 extends through a stuffing box 78 and terminates below in a foot similar to that of Figure 7. The piston rod 77 carries a piston 79 movable in a cylinder 81. The cylinder is connected to an actuating arm 82, through a rubber shock absorbing sleeve 83. Communicating with and carried above the cylinder 81 is an hydraulic chamber 84 containing fluid 85 and a metal bellows 86 mounted between the upper face of chamber 84 and the cover plate 87. The bellows has a charging fitting 88. The opening at the entrance to the bottom of the chamber carries an annular orifice ring 89, through which moves piston rod 77 having a contoured surface 91 to exert an orifice effect in conjunction with ring 89 and control the flow of liquid from the space below the ring to that above it as the piston rod and the piston 79 carried by it moves upwardly into the cylinder 84. Placing the contoured surface on the exterior of the piston rod instead of on the inside of the cylinder as in Figure 8 simplifies machining operations, permits use of an elongated piston 79 with a longer bearing surface and permits a longer stroke of the piston than is practicable with the arrangements of Figure 8.

The arrangement shown in Figure 11 utilizes a simple pneumatic energy absorbing means without the use of hydraulic fluid or springs. In this figure, 92 designates the foot of the compacter having an integral grooved piston 93 carrying packings 94. The piston with its packings is movable in the cylinder 95 supported in a rubber mount 96 on the end of actuating arm 97. The cylinder 95, closed at the top, contains openings 98 to restrict the outflow of air as the piston moves upwardly. Gravity is relied on to restore the piston to the bottom of its stroke.

Arm 97 may be actuated by eccentric 99 and about fulcrum 101 carried by the arm and movable in a resiliently supported bushing 102 having a suspension spring 103 carried by mount 104 and having a rubber cushion 105 beneath it and carried by the mount. This arrangement is provided to show the feasibility of using a resiliently mounted fulcrum and a simple form of absorbing mechanism.

It will be clear from the above description that numerous variations in the structure may be

11

made within the scope of the invention, and that specific embodiments are not limited to the forms shown.

The adjusting means comprising the cables 34 and the actuating means of Figure 12 are illustrated to show one means of adapting the device to meet various uses and various conditions of use. When, for example, the device is not needed it may be lifted completely above the ground or other surface thus making it possible to speed up the propelling vehicle. Under such conditions the device would be unclutched from its actuating shaft 24.

When the compacter is being utilized in breaking ice and is attached to a propelling vessel the adjusting means permits regulation of the height of the device as desired and this may be dependent upon the thickness of the ice to be broken. When ice is being broken on a body of water having current, the device will be directed upstream so that fragments of ice broken off will be carried downstream by the current, thus making the device self-clearing.

The adjusting means is of particular utility when the apparatus is employed in mine field clearing. It may include a counterspring to support a part of the cantilever weight of the device, thus relieving the stress on the cable 34 and assisting in avoiding excessive penetration of the elements into the earth. When the device is traversing muddy terrain, the feet will be elevated to control the depth to which they are driven, and to prevent them from being "bogged down" and rendered ineffective. By suitable adjustment of this character the device can be made to pass through deep mud while still penetrating to a depth sufficient to insure detonation of any mines which could be present. The device has particular utility in clearing mines from rocky terrain since the feet by suitable regulation of the adjuster will enter depressions between rocks and cup-like depressions which would be bridged and passed over by mechanism including large diameter rollers.

In mine field sowing it is customary to utilize barbed wire entanglements surrounding the field in order to render mine clearing more difficult and to impede progress of the pursuing army. This device is capable of passing through barbed wire as an incident to its operation while still exploding all mines and avoiding entanglement of the exploding elements. Instead of driving the device forward continuously as in normal operation, the device may be moved intermittently and stopped at short intervals while the feet are lifted above the wire by the cable and then dropped by releasing the cable to pass through the entangled wire and to explode any mines planted under the wire. In this way, the device operates vertically into the entanglement and no attempt is made to push the elements horizontally through the wire. Consequently, the mines are exploded and the exploder elements pass over the wire directing it underneath the propelling vehicle where it is crushed.

While the compacter element structure shown in Figure 7 has been indicated as the preferred one, it is desired to point out the possibilities of using the energy or shock absorbing elements shown in Figures 8-11 in relations other than those shown. So far as I am aware, it has never before been proposed to employ a Sylphon bellows in combination with hydraulic mechanism as a recuperator. Such an arrangement, particularly where the bellows is mounted in an oil

12

bath, has a highly practical aspect. So long as the possible distortion of the bellows is maintained within the limits of the device, it is capable of effective use for long periods. The usual troubles caused by emulsification of the oil are non-existent since the air is confined within the bellows and changes in the angular position of the oil chamber do not cause mixing of air with the oil.

The Sylphon bellows, by variation in the pressure of the charging gas within it, is flexible enough to permit a wide range of adjustment of its recuperator function, that is, the higher the pressure of the charging gas, the more resistance it presents to deforming forces, and conversely, the lower the pressure of the charging gas, the lower the resistance it opposes to deformation. The bellows, when mounted in an oil chamber, is protected against atmospheric oxidation and mechanical injury, and presents none of the problems that are characteristic of rubber bags which have been used before for this purpose. The Sylphon bellows also offers the advantage of absorbing great amounts of energy through a short stroke of the mechanism, although when combined with hydraulic absorption, almost any length of stroke may be obtained, with appropriate variations of the opposition obtained at particular points in the stroke.

In this description it has been pointed out how the energy absorbing action of the hydraulic fluid may be adjusted to suit particular conditions, that is, by making either the inside wall of the cylinder parabolic in cross section as in Figures 7 and 8, or the piston rod surface parabolic and passing through a fixed orifice as in Figure 10. Obviously, the orifice size may be varied to suit conditions, or it may have such a low retarding value that the compression of the bellows may serve substantially by itself as the energy absorbing means. The bellows may be charged either with air or with any inert gas, such as nitrogen or the like, where particular characteristics are desired. Variation of the response may then be accomplished either by changing the pressure of the charging gas or by varying the cross sectional area of the sylphon or of the hydraulic piston or by any combination of these variables. Obviously, the Sylphon bellows-hydraulic combination may be useful in various relations where energy or shock absorbing action is desired, and where flexibility of design to suit various conditions is desired. The above description is to be construed with these variations in mind and without limitation to the particular embodiments illustrated.

Having thus described the invention, what is claimed is:

1. The combination with a propelling vehicle of a compacting device comprising a frame, a chambered body mounted upon said frame, a ground engaging foot of wear resistant material associated with said chambered body and telescoping therewith, and combined hydraulic and pneumatic energy absorbing means mounted in said body and arranged to oppose relative movement between said foot and said body.
2. The combination with a propelling vehicle of a compacting device comprising a frame, a chambered body mounted upon said frame, a ground engaging foot of wear resistant material associated with said chambered body and telescoping therewith, and energy absorbing means mounted in said body and arranged to oppose movement of said foot into said body, said ab-

sorbing means comprising hydraulic recoil means having a gas filled Sylphon bellows recuperator mounted therein.

3. The combination with a propelling vehicle of a compacting device comprising a frame having a plurality of striking elements mounted thereon, each of said striking elements comprising a cylinder containing hydraulic liquid; a piston movable in said cylinder and having rod-like extensions passing through the cylinder ends; orifice means formed in said cylinder for restricting the flow of liquid from one side of the piston to the other; and a closed metal bellows disposed in the liquid and adapted to be compressed by the liquid displaced by said piston during its movement in one direction in said cylinder.

4. The combination with a propelling vehicle of a compacting device comprising a frame having a plurality of striking elements mounted thereon, each of said striking elements comprising an hydraulic chamber having liquid therein; a piston movable in said chamber and serving to displace liquid from one portion of said chamber to another at a controlled rate; and a flexible metal bellows mounted in said chamber and acting to assist the liquid in opposing movement of the piston in one direction and tending to restore the piston to its initial position.

5. The combination with a propelling vehicle of a compacting device comprising a frame having a plurality of striking elements mounted thereon, each of said striking elements comprising a piston rod movable in a liquid chamber; a piston carried by said rod between its ends and defining rod sections of two different diameters; a second chamber communicating with the liquid chamber on the side of the piston having the smaller rod diameter; and a closed flexible metal

bellows disposed in the second chamber in a position to be compressed by liquid displaced from the liquid chamber by said piston upon recoil and serving to recuperate said piston to its initial position.

6. The combination with a propelling vehicle of a compacting device comprising a frame, a chambered body mounted upon said frame, a ground engaging foot of wear resistant material associated with said chambered body and telescoping therewith, and energy absorbing means mounted in said body and arranged to oppose movement of said foot into said body, said energy absorbing means including hydraulic fluid recoil absorbing means combined with spring recuperator means.
